GASOLINE ADDITIVE MIXTURE

Kenneth A. Smith, Homewood, Ill., assignor to Sinclair Refining Company, New York, N.Y., a corporation of Maine

No Drawing. Application March 7, 1957
Serial No. 644,470

9 Claims. (Cl. 44—53)

My invention relates to a new composition of matter which is suitable for use as an additive to gasoline.

It is conventional to add methanol to gasoline in small amount for the purpose of preventing the freezing of water which may be present in the gasoline. Generally, where methanol is used for this purpose, it is employed in the amount of from about 0.05 to 1% by volume, based upon the volume of the gasoline. It has also been proposed to incorporate small amounts of various trialkyl phosphines into gasoline which contains tetraethyl lead as an anti-knock agent, the function of the phosphine being to reduce the octane requirement increase and preignition which is caused by the tetraethyl lead. Thus, the application of Euphime V. Bereslavsky, Serial No. 512,325, filed May 31, 1955, and now U. S. Patent 2,797,153, teaches the incorporation into gasoline of phosphines of the formula $RR'R''P$ wherein R , R' and R'' are alkyl radicals containing from 1 to 3 carbon atoms, primary or secondary butyl radicals or a primary amyl radical. The amount of phosphine added to the leaded gasoline generally amounts to from 0.005 to 0.025% by volume, based upon the volume of the gasoline. This range is approximately 0.2 to 1.0 cc. of the phosphine per gallon of gasoline.

In order to prevent loss, the methyl alcohol and the phosphine are conveniently added to the gasoline near the points from which the gasoline is distributed, and this is most conveniently done by adding a mixture or concentrate containing the methyl alcohol and the phosphine. The methyl alcohol-phosphine mixture is most conveniently stored in iron or steel tanks which are open to the air. When this is done, however, it is found that oxidation of the phosphine to form acidic materials and consequent rusting of the tank take place. This is definitely undesirable, inasmuch as gasoline conventionally contains a metal deactivator, such as N,N' -disalicylidene-1,2-propane-diamine, which serves the function of reacting with any copper present in the gasoline as a contaminant. Copper is deleterious in gasoline in that it reduces the oxygen bomb stability. The effect of iron as a contaminant in gasoline due to rusting is that the iron as well as copper reacts with the metal deactivator, thereby reducing the amount of deactivator present which can serve the function of reacting with copper.

In accordance with my invention, I have discovered a way in which the oxidation of methanol-phosphine mixtures due to air and the consequent rusting of iron and steel storage vessels containing them can be substantially retarded. At the same time, it is found that the methanol-phosphine mixtures treated in accordance with my invention are considerably less corrosive to copper, brass and other copper-containing metals, so that they have much less tendency to pick up copper from any copper-bearing metal with which they might happen to come into contact during handling.

These beneficial results are obtained in accordance with my invention by incorporating into the methanol-phosphine mixture a small amount of an inorganic compound of manganese or a manganese salt of a carboxylic acid or a mixture thereof. Preferably, I use manganous acetate tetrahydrate and, less preferably, potassium perman-

2

ganate or manganous nitrate, but in their place I can use any of a wide variety of other compounds, such as anhydrous manganous acetate, manganese dichloride tetrahydrate, manganous oxalate dihydrate or trihydrate, manganous orthophosphate trihydrate, manganous sulfate monohydrate, dihydrate or trihydrate, and the like. Hence, my invention involves compositions which consist essentially of from 80 to 98% by volume of methanol and from 20 to 2% by volume of a phosphine of the formula $RR'R''P$ wherein R , R' and R'' are alkyl radicals containing from 1 to 3 carbon atoms, primary and secondary butyl radicals or primary amyl radicals. R , R' and R'' can be the same or different, and mixtures of the phosphines can also be used. Among these phosphines which can suitably be utilized are tri-n-butyl phosphine and triethyl phosphine. In addition to the methyl alcohol and phosphine, my composition also contains from about 2.5 to 100 mg. per liter of the manganese compound or salt, and preferably from 15 to 50 mg. per liter. In use, my composition is simply blended into leaded gasoline in amount such that the phosphine added to the gasoline is from about 0.2 to 1.0 cc. per gallon.

In preparing my composition, the manganese compound or salt can first be dissolved in the methanol and the methanol then mixed with the phosphine or mixture of phosphines. Also, if desired, the manganese compound or salt can be dissolved in the methanol and the solution then mixed with the phosphine or mixture of phosphines and a further quantity of methanol. Other methods of preparing my composition will suggest themselves to those skilled in the art.

The following examples illustrate various embodiments which fall within the scope of my invention, and further illustrate the practice thereof.

A series of corrosion tests under oxidizing conditions were made by bubbling air through a concentrate composed of 95% by volume of methanol and 5% by volume of tri-n-butyl phosphine in the presence of one or more metals. Corrosion rates were determined by analyzing the concentrates or by measuring the weight loss of the metals. Further information concerning the test conditions and information concerning the test results are set forth in Table I.

In runs 10 through 14, nickel, chromium, manganese and molybdenum (metals which might be present as impurities in steel) were added in trace amounts to portions of the concentrate in the form of powdered nickel, potassium dichromate, potassium permanganate and ammonium molybdate. In 43 hours, 4 of the 5 samples subjected to test, including the base concentrate with no additives, had picked up large amounts of iron, exceeding 200 p.p.m., from small ingot iron discs that were present. The concentrate containing potassium permanganate, however, showed no iron pick-up in 43 hours and the test was continued to 162 hours at which time it still showed essentially no iron corrosion. Additional tests with potassium permanganate in various concentrations (runs 18, 20 and 21) also showed no iron corrosion. During one test (run 18) a copper strip was added to the concentrate for the final 42 hours of the test to determine whether potassium permanganate might also eliminate copper corrosion. Copper pick-up of approximately 300 p.p.m. occurred during this time. As N,N' -disalicylidene-1,2-propane-diamine (MDA) is at times blended into methanol-phosphine concentrates before they are added to gasoline, a test (run 23) was made with both potassium permanganate and the metal deactivator present. The results of this test showed that potassium permanganate is just as effective in eliminating iron pick-up in this combination.

Other oxidation tests were made in the presence of the ingot iron discs and they showed that an oxidized concentrate already containing large amounts of iron continued to pick-up iron at a steady rate (run 19), and that a commercial anti-oxidant, di-butylparacresol, is effective in reducing iron corrosion (run 22). A test was also made in which the concentrate was oxidized in the absence of iron by air blowing for 61 hours and an iron disc was then added to the concentrate (run 30). In 5½ hours the solution picked up approximately 50 p.p.m. of iron, showing that oxidation of the phosphine-methanol concentrate causes heavy rusting of an iron vessel containing it. A second oxidation test in the presence of methyl alcohol and absence of iron was made with potassium permanganate added to the concentrate (run 37). After 187 hours, a carbon disulfide colorimetric test showed essentially no oxidation of the phosphine. In contrast, a qualitative test with the carbon disulfide showed almost complete oxidation of the phosphine in 18 hours without potassium permanganate.

Concentrates containing only MDA (runs 31 and 32) showed heavy corrosion towards steel, copper and white metal, and essentially no corrosion of aluminum and Monel. Samples of concentrates containing potassium permanganate and MDA (runs 35 and 36) showed lower corrosion of white metal, greatly reduced steel corrosion, and also a substantial reduction in copper corrosion. Other compounds containing manganese were also found to be effective. Manganese acetate (chemically pure manganese acetate tetrahydrate) and manganese nitrate used in runs 44 and 45, respectively, were just as effec-

tive as potassium permanganate in reducing copper and iron corrosion.

EXAMPLE II

The various tests performed in accordance with this example were run on a 95% by volume methanol-5% by volume tri-n-butyl phosphine mixture by oxidation with air in the manner described in Example I. To study the effect of manganese acetate tetrahydrate concentration, a series of oxidation tests were made with concentrations of the manganese acetate tetrahydrate ranging from 2½ to 100 mg. per liter of concentrate. These tests are reported in Table II, as runs 53 through 58. The amounts of tri-n-butyl phosphine oxidation and iron pick-up in 66 hours were negligible at all concentrations. Thus, a concentration as low as 15 mg. of manganese acetate tetrahydrate per liter of concentrate gives adequate protection against iron pick-up with a large safety factor. The data also show that copper attack can also be substantially reduced by employing a manganese acetate tetrahydrate concentration of at least 15 mg. per liter of concentrate.

As a specific illustration of the use of a composition falling within the scope of my invention, a concentrate is first prepared composed of 95% by volume of methanol and 5% by volume of tri-n-butyl phosphine. To the concentrate is added 100 mg. of manganese acetate tetrahydrate per liter of concentrate. The concentrate containing the tetrahydrate is incorporated into leaded gasoline in the amount of 0.26% by volume, based upon the volume of the gasoline.

NOTE.—TBP is tri-n-butyl phosphine, rubber solvent is a petroleum solvent, Mn(Ac)₂ is manganous acetate tetrahydrate.

I claim:

1. A composition of matter useful as a gasoline additive consisting essentially of from 80 to 98% by volume of methanol and from 20 to 2% by volume of a phosphine of the formula RR'R''P wherein R, R' and R'' are alkyl radicals selected from the group consisting of alkyl radicals containing from 1 to 3 carbon atoms, primary and secondary butyl radicals and primary amyl radicals, the said composition also containing from about 2.5 to 100 mg. per liter of a material selected from the group consisting of potassium permanganate, manganous nitrate, manganous acetate tetrahydrate, anhydrous manganous acetate, manganese dichloride tetrahydrate, manganese oxalate dihydrate, manganous oxalate trihydrate, manganous orthophosphate trihydrate, manganous sulfate monohydrate, manganous sulfate dihydrate and manganous sulfate trihydrate.

2. The composition of claim 1 wherein RR'R''P is tri-n-butyl phosphine.

3. The composition of claim 1 wherein said material is potassium permanganate.

4. The composition of claim 1 wherein said material is manganous nitrate.

5. The composition of claim 1 wherein said material is manganous acetate tetrahydrate.

6. A composition of matter useful as a gasoline additive consisting essentially of from 80 to 98% by volume of methanol and from 20 to 2% by volume of a phosphine of the formula RR'R''P wherein R, R' and R'' 50

are alkyl radicals selected from the group consisting of alkyl radicals containing from 1 to 3 carbon atoms, primary and secondary butyl radicals and primary amyl radicals, the said composition also containing 15 to 50 mg. per liter of a material selected from the group consisting of potassium permanganate, manganous nitrate, manganous acetate tetrahydrate, anhydrous manganous acetate, manganese dichloride tetrahydrate, manganese oxalate dihydrate, manganous oxalate trihydrate, manganous orthophosphate trihydrate, manganous sulfate monohydrate, manganous sulfate dihydrate and manganous sulfate trihydrate.

7. The composition of claim 6 wherein RR'R''P is tri-n-butyl phosphine and wherein said material is potassium permanganate.

8. The composition of claim 6 wherein RR'R''P is tri-n-butyl phosphine and wherein said material is manganous nitrate.

9. The composition of claim 6 wherein RR'R''P is tri-n-butyl phosphine and wherein said material is manganous acetate tetrahydrate.
